(57) CLAIM

The ornamental design for a tank top, as shown and described.

DESCRIPTION

FIG. 1 is a front view of a tank top according to the design; FIG. 2 is a rear view thereof;

FIG. 3 is a right side view thereof;

FIG. 4 is a left side view thereof;

FIG. 5 is a front perspective view thereof;

FIG. 6 is a rear perspective view thereof;

FIG. 7 is a rear view thereof shown in an environment of use; and,

FIG. 8 is a rear view thereof shown in an environment of use with rear panels thereof shown in a tied configuration.

The portions of the tank top shown in broken lines in FIGS. 1-2 and 5-6 do not form part of the claimed design. The broken line showing of the hands, arms, legs, torso, neck, and head in FIGS. 7-8 is for the purpose of illustrating portions of the environmental structure and forms no part of the claimed design.
